UNITED STATES PATENT OFFICE

LOUIS D. SUMMERS, OF DECATUR, ILLINOIS, ASSIGNOR TO LEADER IRON WORKS,
OF DECATUR, ILLINOIS

HEAT ECONOMIZER

Application filed December 5, 1927. Serial No. 237,783.

My invention relates to heat economizers adapted to be used in operative connection with a heating plant; an object being in this economizer particularly to provide means for causing the normally wasted hot products of combustion emanating from the combustion chamber of a heating plant to give up the greater percentage of their heat to water, steam or other heat absorbing mediums through the principle of counterflow while the gases are moving on their way to a discharge flue communicating with the heating plant.

A further object of my invention is to provide an economizer in which the hot gas flows countercurrent to the fluid to be heated.

An object of my invention is to provide in an economizer of this character a means of easy access to the inner chambers of the economizer and to provide an easily detachable hood at the top thereof adapted to merely rest in operative position upon the shell of the economizer when assembled.

A particular object of my invention is found in the fact that in its simple and convenient details of construction it may be easily and quickly installed in a heating plant that has already been in operation and that it is adapted to operate successfully within a large heating plant or to be used in connection with an ordinary house furnace; the principle of operation being practical in either case.

I attain the objects of my invention in the economizer described in the annexed specification recited in the claim and illustrated in the accompanying drawings in which like reference numerals indicate like parts in the several figures.

Fig. 1 is an elevation partly in section of my economizer.

Fig. 2 is a vertical section.

Fig. 3 is a top view of my heat economizer.

Fig. 4 is a horizontal cross section taken on the line 4-4 of Fig. 1.

Fig. 5 is a small sectional view showing the inclined position of upper and lower headers —6— and —7—.

My heater will conserve the heat that is wasted when hot gases pass directly from a combustion chamber to a discharge flue.

Referring now to the operating details of my economizer I provide an upright drum —1— constructed so as to form within its enclosure an upper hot gas receiving chamber —2— normally covered by a conveniently detachable hood —3— and a lower gas chamber —4— at the base of the drum. Between these gas chambers I provide an intermediate water chamber —5— with an upper tube plate —6— and a lower tube plate —7— circumferentially secured to the wall of the upright drum and carrying a group of upright gas tubes —8— providing passage for the hot products of combustion from the upper gas chamber to the lower gas chamber through the water chamber. Tube plates —6— and —7— are slightly inclined in order that any vapor forming within the water chamber may collect at one side of the said chamber and be easily released through pipe —19— thus avoiding cracking and popping.

In the construction of my economizer I provide a by-pass gas tube —9— operatively connected to a centrally disposed opening —10— in hood —3—; which pipe is connected with the gas discharge flue —11— and has at the junction point with said flue a thermostatic damper —12— adapted to automatically control the movement of gases through by-pass tube —9—. This thermostatically controlled damper is the subject of a separate and distinct application for patent and is not claimed in this case.

The purpose of the by-pass pipe —9— and the damper therein is to provide a quick and easy direct passage of the hot products of combustion coming from the combustion chamber of a heating plant through pipe —13— into the upper gas chamber —2— so that these gases may when it is desired pass up through by-pass pipe —9— and out through gas discharge pipe —11—. This arrangement may be required occasionally when the economizer is connected with a domestic heating plant until the fire in the combustion chamber is well started, after which the damper —12— is closed whereupon the thermostatically controlled element —14— therein expands and releases the damper plate —15— to pivotally turn on its axis —16—.

by the gravity force on the counterbalance —17— of the plate.

Thus when damper plate —15— is closed the gases will pass downwardly through the tubes 8 and give up their heat to the water or steam surrounding the said tubes.

Cold water enters chamber 5 through pipe 18 and comes first into contact with the coldest portion of pipes 8. It then rises to the hottest portion of the said pipes in the top of the heater from which it escapes at a high temperature through pipe —19—.

It will be seen that a convenience for handling hood —3— is provided in handles —20— and —21—.

A clean-out door —22— for lower gas chamber —4— is provided.

Having thus described the nature of my invention what I claim is:

20 A fire tube economizer of the character described comprising an upright shell, spaced inclined tube sheets dividing the shell into chambers, upright fire tubes secured in the tube sheets, a hot gas inlet and outlet for the 25 upper chamber and a hot gas outlet and clean-out opening for the lower chamber, a fluid inlet and outlet for the chamber between said tube sheets, and an unsecured removable annular flanged cover plate normally fitting on 30 top of said shell over said upper chamber and provided with integral hand hold loops.

In witness whereof, I hereunto set my hand this 11th day of November, A. D., 1927.

LOUIS D. SUMMERS.
